CARD NOVELTY

Application filed December 23, 1930. Serial No. 504,408.

This invention relates to gift cards and like articles classifiable as card novelties.

My invention is directed toward enabling production in an expeditious and economical manner from metallic sheet material, of composite card novelties characterized by having opposite faces in relief and either of the same of different designs, and which are effectively strengthened by intermediate plies 10 against being easily deformed or bent notwithstanding the use of very thin material in their fabrication.

The above desideratum I attain as herein-after described in detail, by first forming 15 from very thin adhesive-backed metallic sheet material a blank consisting of a series of edge-attached plain and embossed (or otherwise embellished) sections all of the same profile; then moistening the adhesive 20 backing of the blank; and finally folding the blank to bring its several edge-attached sections into coincidence with the embossed sections outermost to serve as the face and back of the card novelty, while the intermediate 25 sections serve as fillers for the purpose of thickening and stiffening the card novelty.

In connection with card novelties intended to accompany gifts, it is a further aim of my invention to provide for the application 30 of signatures or other inscriptions by forming one or both of the face sections of the blank with apertures, and by incorporating, incident to folding of the blank as aforesaid, sheets of paper or the like for exposure at 35 the openings of the apertured faces of the resultant card novelty.

A still further object of my invention is to secure in card novelties the advantages of diversified finishes possible with use of metal 40 in their fabrication, through burnishing, color printing, high spot polishing, enameling, etc.

In the drawings Fig. I is a diagrammatically represented section of metallic sheet 45 material of a kind which I prefer to employ in the fabrication of my improved card novelties.

Fig. II shows a card novelty blank die stamped or otherwise cut from the material 50 of Fig. I.

Fig. III is a sectional view of the stamping, taken as indicated by the arrows III-III in Fig. II, and showing in dotted lines the manner in which the blank is folded to produce the finished card novelty. 55

Fig. IV is a diagrammatic cross sectional view of the finished card novelty.

Fig. V is a view corresponding to Fig. II showing another type of blank intended to form, when folded, a greeting card. 60

Fig. VI is a sectional view similar to Fig. III showing how the blank of Fig. V is folded and the manner of incorporating sheets of paper or the like for ultimate exposure through openings in the face sections of the 65 blank shown in Fig. V; and,

Fig. VII is a diagrammatic cross sectional view of the gift card formed from the blank of Fig. V.

In the practice of my invention, I employ 70 sheet material of the kind diagrammatically illustrated in section in Fig. I consisting of a layer 10 of very thin pliable metal like brass, copper, bronze or aluminum, whereto is secured, through interposition of a layer of adhesive 11, a layer 12 of correspondingly thin paper which is in turn coated with a layer 13 of adhesive. From sheet material characterized as just explained I die stamp or otherwise cut a blank, such as shown in Fig. II, 80 with similarly profiled edge-attached sections whereof there are in the present instance three, which are designated respectively by the numerals 14, 15 and 16. For convenience of exemplification, the sections 14, 15 and 16 85 of the blank are profiled to represent the figure of a soldier. As shown, the sections 14 and 15 are differently embossed in this instance to bring out the lines of the figure and to serve ultimately as the front and back of the 90 finished card novelty, while the third section 16 of the blank is plain, i. e. unembossed.

With a blank thus prepared, I moisten the adhesive backing 13 and then fold the sections 14-16 into coincidence after the manner indicated in Fig. III, that is to say: I first swing the section 16 over upon the section 15, and then swing the section 14 in turn over the section 16. This operation results in a composite card novelty having the cross section 100

shown in Fig. IV which I maintain under pressure for a time interval sufficient to insure setting of the adhesive. As a consequence of folding in the manner described, the plain section 16 of the blank is disposed intermediate the embossed frontal and rear sections 14, 15. The section 16 therefore serves to materially stiffen the card novelty and to increase its resistance against easy deformation or bending after the adhesive has once set. The attractiveness of the card novelty may be enhanced through various artifices possible in the treatment of metal, for example, the blank may be printed with different colors incident to die stamping and embossing; or it may afterwards be burnished, and in addition, the raised areas may be polished to produce contrasting dull and high light effects. By virtue of the thinness of the metal employed, my card novelty is not appreciably heavier than similar novelties made from cardboard or paper, notwithstanding the fact that it is thicker and stiffer due to the embossing of its front and rear faces.

Referring now to Fig. V, I have there shown a blank for a gift card novelty, which blank, like the one of Fig. II has three similarly configured edge attached sections 14a, 15a and 16a, these sections being in this case of rectangular oblong outline. As in the first instance, two of the sections, to wit the sections 14a, 15a are differently embossed while the third section 16a is plain. It will however be noted here that the embossed sections 14a, 15a are apertured as at 17, 18. The method followed in folding the blank of Fig. V is identical with that described in connection with the folding of the blank of Fig. II, that is to say, the section 16a is first swung over the section 15a and the section 14a finally swung over upon the section 16a but, incident to such folding, I insert between the several sections sheets 19 and 20 of paper or other non-metallic material capable of being written upon, the surfaces of which, after the blank has been folded to produce the gift cards, are exposed through the apertures 17, 18 in the faces 14a, 15a for signatures or other personal inscriptions which the sender of the card may wish to apply. On the other hand, the names may be printed or engraved on the paper slips previous to their incorporation in the cards; or, again if desired, pictures or photographs may be used in lieu of the paper sheets.

It is of course to be understood that I do not wish to be limited to the specific profile configurations, nor the specific embossed designs illustrated herein since these are obviously open to extensive variation in practice. Figured card novelties such as shown in Fig. II can be used as toys, and, if desired they may be provided either with integrally

formed or separately attached bases to support them in upright position.

Having thus described my invention, I claim:

1. The method of fabricating card novelties from thin adhesive-backed metallic sheet material, by forming from such material a blank with unembossed edge-attached profile sections in series with a pair of similarly profiled edge-attached embossed sections; moistening the adhesive backing of the blank; and infolding the plain sections of the blank between the embossed sections. 70

2. The method of fabricating card novelties from thin adhesive-backed metallic sheet material, by forming from such material a blank with unembossed edge-attached profile sections in series with a pair of edge-attached similarly profiled but differently embossed sections; moistening the adhesive 80 backing of the blank; and infolding the plain sections of the blank between the embossed sections. 85

3. The method of fabricating card novelties from thin adhesive-backed metallic sheet material, by forming from such material a blank with similarly profiled edge-attached plain sections in series with a pair of similarly profiled edge-attached but apertured sections; moistening the adhesive backing of the 95 blank; and incident to infolding the plain sections between the apertured sections, interposing sheets of paper or the like for ultimate exposure in the openings of the said apertured sections. 100

4. The method of fabricating card novelties from thin metallic adhesive-backed sheet material, by forming from such sheet material a blank with similarly profiled edge-attached plain sections in series with a pair of similarly profiled edge-attached but embossed apertured sections; moistening the adhesive backing of the blank; and, incident to infolding the plain sections of the blank between the embossed apertured sections, interposing sheets of paper or the like for exposure ultimately in the openings of the said embossed apertured sections. 105 110

5. A composite card novelty formed from thin metallic sheet material having an adhesive backing and comprising correspondingly profiled embossed front and rear connected thicknesses, and an edge-attached similarly profiled intermediate thickness. 115

6. A composite card novelty formed from thin metallic sheet material having an adhesive backing, and comprising correspondingly profiled apertured front and rear face thicknesses, similarly profiled plain intermediate thicknesses, and interposed sheets of paper or the like exposed through the apertures of the face thicknesses. 120 125

7. A composite card novelty formed from thin metallic adhesive-backed sheet material and comprising correspondingly profiled em- 130

bossed apertured front and rear face thicknesses, similarly profiled but plain intermediate thicknesses, and sheets of paper or the like interposed for exposure through the apertures of the aforesaid face thicknesses.

5 In testimony whereof, I have signed my name at Allentown, Pennsylvania, this 20th day of December, 1930.
